UNITED STATES PATENT OFFICE.

CARL AUGUST RUDQVIST, OF STAKET, SWEDEN.

CENTRALIZED OPERATING MECHANISM FOR INTERNAL-COMBUSTION MOTORS.

Application filed May 3, 1923. Serial No. 636,350.

To all whom it may concern:

Be it known that I, CARL AUGUST RUDQVIST, a subject of the King of Sweden, residing at Staket, in the county of Stockholm 5 and Kingdom of Sweden, have invented new and useful Improvements in Centralized Operating Mechanism for Internal-Combustion Motors, of which the following is a specification.

My invention relates to a new and useful improvement in operating mechanisms for internal combustion motors, and has for its object to so construct devices of this description as to make them exceedingly simple, 15 convenient and accessible, in order to make it possible to perform all necessary operating movements from one place.

By means of the device forming the subject-matter of this invention an electric current is closed to an igniting plug in the combustion chamber of the motor, in order to start the motor immediately in its cold state 20 without particular heating means. In addition, an electric current may be closed 25 through an auxiliary electric starting motor, said starting motor being automatically thrown in so as to impart movement to the combustion motor.

The invention also comprises means for 30 braking the speed of the motor, particularly in order to facilitate reversing, but also to stop the motor, when necessary.

This operating mechanism facilitates the 35 performance of necessary operating movements in a determined order, thus eliminating all disturbance.

With these and other objects in view this 40 invention consists in the details of construction and combination of elements herein-after set forth and then specifically designated by the claims.

In order that those skilled in the art to 45 which this invention appertains may understand how to make and use the same, the construction and operation will now be described in detail, reference being made to the accompanying drawings, in which:—

Fig. 1 is a plan view of the apparatus, 50 showing the index plate in the upper housing, Fig. 2 is a schematic view of a combustion engine arranged according to the invention, Fig. 3 is a plan view of the apparatus with the upper housing removed, and showing the connections to the electric battery. Fig. 4 is a sectional view on the line IV—IV, 55 Fig. 3, and Fig. 5, a sectional view on the

line V—V, Fig. 3. Figs. 6, 7, 8, 9, 10, 11, 12 and 13 show details.

The operating lever 1 is provided with an indicator 2 adapted to travel over a scale 60 on a plate 3, fixed on the upper housing 4. The scale is graduated for "forward" and "back" and for this purpose is marked with letters I (ignition) S (starting) and F (fuel) on each side of the mark 0 (zero), 65 one side corresponding to "forward" and the other side to "back." The hub 5 of the starting lever 1 by means of a pin 6 is attached to a hub 7 extending from a double-armed element 8, pivoted on a tube 9 in the 70 bottom plate 10.

The right arm of element 8 (Figs. 3 and 4) is formed into a hub 7¹, provided with a contact member 11 of electrically conductive material, by means of threads attached 75 to a shaft 12 with a rifled knob 13, fixed to shaft 12 by means of a pin 14. The knob is provided with an arrow 13¹, in normal position in alinement with an arrow on the housing 4, the object of the arrows being 80 to show whether the knob has been turned or not. A spring 15, wound around the shaft 12, serves for pressing the contact member 11 downward. Contact member 11 and shaft 12 are disposed in a non-conducting socket 85 16 fixed on the hub 7¹. By lifting the contact member 11 against the pressure of the spring 15 and at the same time turning the knob 13 one quarter of a turn, the contact member 11 may be secured in a lifted position, the shaft 12 being provided with pins 90 17 extending from two sides of the shaft, which during the turning motion will be brought to rest upon a raised surface 18 of the socket 16, against abutment projections 95 19 (Figs. 3 and 4) to limit the movement. Shaft 12 with knob 13 extends outside of the housing 4 through an opening or slot 20, so designed as to allow the shaft 12 to move freely during the turning motion of 100 element 8. Below the contact member 11 there are two circular metal contact rails 21 and 22, shown from one side in Fig. 13. These rails are fixed in circular grooves in a ring 23 of electrically insulating material. 105 In order to break the contact between the contact member 11 and the middle portions of rails 21, 22, said portions of the rails are somewhat recessed as at 24, Fig. 13. The rails are provided with contact pins 25, 110 26 for the electric wires 27, 28.

The left arm of element 8 (Figs. 3 and

2

4) is provided with three hubs, one of which is situated at the middle part of the arm and represented by the numeral 29, the others 30 and 31 being placed at each side 5 of hub 29 and similar to each other. Hub 29 is provided with a metal contact member 32, shaft 33, spring 34 and insulating socket 35, all of the same design as the corresponding parts 11, 12, 15, 16 of the hub 7¹ of the 10 left arm, the only difference being that shaft 33 is provided with a washer 36 instead of the rifled knob of shaft 12, said washer being situated on the inside of housing 4. Each of the hubs 30 and 31 is provided 15 with a pin 37 having an electrically conducting head 38, and at the upper part of the pins there are secured collars or washers 39 by means of cotter pins 40. Each pin 37 is surrounded by a pressure spring 41, 20 the whole being enclosed in an insulating socket 42, attached to the hub. Below the different positions of contact member 32, there are arranged circular metal contact rails 43, 44, 43¹ and 44¹ arranged at intervals as shown in Figs. 3 and 12 in the circular grooves of the insulating ring 23. In these grooves are also fixed the contact rails 46, 47, 46¹ and 47¹ below the different 25 positions of the heads 38. The rails are 30 provided with contact pins 48, 48¹, 49, 49¹, 50 and 50¹ for the electric wires 51, 51¹, 52, 52¹, 53 and 53¹ respectively.

As will be understood from Fig. 12, the 35 contact rails are arranged with a certain clearance space. In Fig. 12 the rail pieces are viewed from the inside and spread out to a plane figure. The rail pieces shown in Fig. 12 being those arranged in the inner groove of the insulating ring, the corresponding outer rails 46¹, 43¹, 44¹ and 47¹ (Fig. 3) are situated behind the rails shown. The element 8 being in the position shown in Fig. 3, the indicator pointing at 0, all the 40 contact members 11, 32, 38, 38 are free from the contact rails, no circuit being closed. By turning element 8 at such an angle, that the indicator points at 1, contact will be 45 formed between the member 11 and rails 21, 22, thus closing the circuit from the battery B through wires 28, 27 and the igniting plug 55 of the main motor M, the return circuit from the igniting plug being through the frame of the engine in the usual manner. At the same time contact will be 50 formed between the contact member 32 and the contact rails in such a manner, that by turning the indicator to the left (Fig. 1), the member 32 will come into contact with the "back" rails 43, 43¹ and by turning to the right, contact will be formed with the "forward" rails 44, 44¹. By this arrangement of the contacts, the positive pole of the battery will be connected to one or the other of the poles of the electric starting motor 56, thus determining the turning di-

rection of same. The heating of the igniting plug having been accomplished in about one quarter of a minute by means of a resistance element (not shown), for the purpose of warming the fuel as it is delivered to the combustion chamber, the next operation will be to turn element 8 with the indicator pointing at S. The contact member 38 of hub 30 will thereby be thrown into contact with rails 43, 43¹ if "back" be desired. In case of "forward" being desired, element 8 must be turned with the indicator pointing at S on the right side (Fig. 1), the contact member 38 of hub 31 will then be thrown in with rails 44, 44¹. By this operation the negative pole of the battery will be connected to the other pole of the starting motor. With the type of starting motor generally chosen for the purpose in question, an axial movement of the rotor will be accomplished before the motor starts to run. By this axial movement of the rotor a pinion 57 on the motor shaft will be carried into mesh with a gear wheel 58 on the shaft 59 of the combustion motor M. The starting motor, immediately after the axial movement of the rotor, being set into motion by the electric current, the main motor M begins to rotate in the direction desired. It must be noted, that during all the operations mentioned above, which are carried out by means of the starting lever 1, this lever must be held steady in the different 90 positions; as the element 8 will return to the zero-position, as soon as the lever is 100 let free. Springs 60 and 61 being fixed between projections 62 and 63 of element 8 and pins 64 and 65 on the bottom plate 10, will cause this automatic-return movement of element 8. The contact rails 44, 46 and 46¹, 47¹ are electrically connected by means of conducting members 66 and 67, to facilitate the passage of the electric current.

The arrangement for braking the speed 110 of the motor, for the purpose of reversing or stopping same, comprises a braking lever 68, rigidly attached to a shaft 69, rotatably mounted in the tubular part 9 of bottom plate 10. At the lower end of the shaft, there is attached a hub 70 with an extending 115 arm 70¹, and below this hub a lever 71.

It is a matter of great importance that on starting the motor, the pinion 57 of the auxiliary starting motor will not be damaged by the gear wheel 58 of the main motor, as may easily be the case if the main motor is rotating when the starting motor is thrown in. With this object in view, the starting lever is so combined with the brake 120 and with element 8, that the operations of levers 1 and 68 for starting and braking, may only be undertaken in a certain determined order, as will be set forth in the following.

The fuel pumping member 75, shown dia-

grammatically in Fig. 2, is operated on its pressure stroke by a reciprocating member (not shown) connected to the shaft of the motor M in any well known manner so as to 5 oscillate synchronously with the rotation of said shaft, said reciprocating member being adapted to strike the pumping member 75 once during each revolution, thus causing the pump to inject fuel into the cylinder. 10 The suction stroke of the pump is produced by means of a spring encircling the pumping member 75 as shown in Fig. 2. A lever 76 is pivotally mounted on a pin 77 carried by the motor casing, said lever having a 15 bent end adapted to engage the pumping member 75 and maintain the same out of reach of the reciprocating operating member. For operating the lever 77 a spring 78 is connected at one end thereof to said lever 20 and at its opposite end to a lever 79 pivoted at 101 on the motor casing, to which lever is secured a line or wire 80, passing over a guide roll 81 and attached to the lever 71 mentioned above. The position of lever 71 25 will determine the position of lever 76 and consequently the acting or the non-acting of the fuel pump, and lever 71 is locked in position by means of a pin 82 at the end of arm 70¹, said pin by means of a spring 30 83 being forced into a hole in a collar 72 on base plate 10. The fuel pump plunger, in the usual manner during the active stroke is forced inward against the action of the spring above referred to, said spring serving 35 for imparting movement to the plunger during the suction stroke.

Located in a circular groove in the bottom plate 10, below the right arm of the member 8, is a segmental member 86 carrying at its 40 underside a pin 87 which extends into the opening in collar 72 and into contact with the pin 82 above described. The member 86 is cut out at the upper side thereof to provide a pair of upwardly extending projections or lugs 85, as shown in Figs. 9 and 10, the inner sides of said lugs being curved or inclined. The member 86 is normally held in contact with the arm of the member 8 by 45 means of a spring 87', so that no pressure is 50 exerted by the pin 87 on the pin 82. Upon rotating the operating lever 1, however, to the position where the indicator is in alignment with F at either side of the scale, a part 84 of the arm of member 8 will ride up 55 on the curved side of one of the lugs 85, thus depressing the member 86 and causing its pin 87 to force the pin 82 down out of the opening in collar 72, thereby releasing the lever 71, whereupon a spring 88 (Fig. 2) 60 acts on the lever 79 and relieves the tension of spring 78, thus rendering the lever 76 inoperative and permitting the fuel pump to be operated.

After this operation, the operating lever 1 65 is released and automatically returns to zero,

as mentioned above. If the motor is sufficiently heated, it will now run normally. Should this not be the case the starting operation must be repeated. For reasons mentioned above, it is necessary to brake and 70 stop the speed of the motor before starting anew. For this purpose another locking device is provided, comprising a circular segmental part 90 (Figs. 3, 7 and 8) arranged in the circular groove in the base plate 10, 75 and provided with locking projections 89 with raised surfaces (Fig. 7) similar to the projections 85 of member 86 above described. Element 8 carries a part 91, which on turning the element will come into contact with either one of the raised projections 89 and thus force the member 90 downward. The circular part 90 also carries a pin 92 which projects into a hole in a collar 74 on base plate 10, the end of which pin is screwed 80 into a strap 93. A spring 94 forces the pin 92 upward. The strap 93 embraces a sector-formed part 95 of hub 70, provided with a wedge-formed part 96. For braking the motor, the lower part of lever 79 (Fig. 2), 85 on each side of pivot 101 is connected to a brake band 102 of generally known design, combined with a sheave 103 on the motor shaft 59.

The purpose of this brake is to enable the operator to reverse the motor rapidly and with the least possible loss of time. When starting the motor, it may happen that the electric starting motor is thrown off too soon, with the result that the main motor will 90 stop, whereupon the operator may desire quickly to throw in the starting motor. The main motor may not, however, have come to a complete stop and if the starting motor is 95 operated so as to bring the pinion 57 into mesh with the gear 58 while the main motor is rotating considerable damage might be done to the teeth of the pinion. By means of this braking mechanism, however, this 100 danger is entirely eliminated. The brake 105 band 102 is so connected with the lever 79 that it will be tightened on the sheave 103 110 when the lever 79 is swung on its pivot by the tightening of the cable 80.

In the braking position of lever 68 the 115 wedge 96 will force down the pin 92 and locking projections 89, thus unlocking element 8 and facilitating a new starting operation. In this position member 90 is locked by means of a lip 97, said lip by 120 means of a spring 98 and pins 99 being carried on the base plate 10. For bringing the lip into, as well as out of locking position, there are arranged co-acting surfaces on element 8 and the arms 104 of the lip. A series of holes in lever 71 facilitate an adjustment of the attachment point of wire 80. The collar 72 carries an arm 73 with a recess 100 for receiving the pin 82 when braking is 125 completed. The fuel pump will be thrown 130

out before the beginning of the braking action; and the spring will be stretched when the brake band 102 is set around sheave 103.

Movement will be imparted to pin 92 at every starting operation. The lever 1 and element 8 being turned at starting, the member 90 will be unlocked from the lip 97, said lip being forced to move in the direction of the centre of the apparatus by the action of a cam surface on the bottom side of element 8. (This surface is shown in Fig. 4, a clearance being shown in the figure between lip 97 and the surface; for the sake of clearness). When the surface strikes one of the projecting arms 104, 104 of lip 97, the lip will be moved out of locking position and the pin 92 consequently will be free to move upward by the action of spring 94. The element 8 having been turned back from starting position, the projections 89 of member 90 will prevent the turning of element 8 for a new start, before braking the motor. The braking is accomplished by turning lever 68, the lever 71 and sector 95 being turned at the same time, thus forcing down member 90 by means of projections 96, as stated above.

Essentially, this invention relates to an operating mechanism for internal combustion motors, provided with an electric motor for starting or reversing the motion, the object of the invention being to provide devices for braking the motor, shutting off the fuel-supply or the ignition, conducting electric current to the starting motor in such a way that the same will rotate in either direction and, in case of the motor being a crude-oil motor, for putting one or more electric glowing bodies for quick starting ignition into action, all of which devices are brought together in one apparatus and so associated with each other that the fuel-supply and the ignition are cut off before the braking, and that operation of the starting motor is prevented until an operation for stopping the main motor is completed.

Various modifications may be made without departing from the spirit and scope of this invention, which is not to be limited to the particular details shown and described. The brake arrangement may be designed as a hydraulic, magnetic or pneumatic brake, the lever 79 being connected to suitable elements, such as valves or electric contacts and circuit breakers. In this case, the lever may act directly upon these elements, or may be connected to the elements by means of link arrangements or electric conductors. If the operating gear is designed for a motor with electric spark ignition, the spark must be thrown in shortly before the fuel supply is put into function.

The device is not limited to a certain type

of motor; it may be used for 2-cycle as well as for 4-cycle motors, and for explosion motors as well as for Diesel-motors.

The object of securing the contact member 11 in a raised position, is to prevent the current from passing through the igniting plug 55 in case of reversing, if the motor should be warm enough for igniting the fuel without necessitating the heating of the plug.

Having thus described the nature of my invention, what I claim as new and desire to secure by Letters Patent, is—

1. The combination of an internal combustion engine having an electric ignition plug, an auxiliary electric starting motor, means for supplying an electric current to said plug and motor, a device for supplying fuel to said engine, means for maintaining said device inoperative, and movable means operative in successive steps to close the circuit through said ignition plug, then through said starting motor and then to release said fuel supplying device thereby to start the engine.

2. The combination of an internal combustion engine having an electric ignition plug, an auxiliary electric starting motor, means for supplying an electric current to said plug and motor, a device for supplying fuel to said engine, means for maintaining said device inoperative, movable means operative in successive steps to close the circuit through said ignition plug, then through said starting motor and then release said fuel supplying device thereby to start the engine, and means automatically operative upon the return of the operating means to normal position to render the fuel supplying device inoperative.

3. The combination of an internal combustion engine having an electric ignition plug, an auxiliary electric starting motor, means for supplying an electric current to said plug and motor, a device for supplying fuel to said engine, means for maintaining said device inoperative, movable means operative in successive steps to close the circuit through said ignition plug, then through said starting motor and then to release said fuel supplying device thereby to start the engine, means automatically operative upon the return of the operating means to normal position to render the fuel supplying device inoperative, and manually operable means operative while said fuel device is inoperative to brake the speed of rotation of the engine.

4. The combination of an internal combustion engine having an electric ignition plug, an auxiliary electric starting motor, means for supplying an electric current to said plug and motor, a device for supplying fuel to said engine, means for maintaining said device inoperative, movable means op-

- erative in successive steps to close the circuit through said ignition plug, then through said starting motor and then to release said fuel supplying device thereby to start the engine, means automatically operative upon the return of the operating means to normal position to render the fuel supplying device inoperative, manually operable means operative while said fuel device is inoperative to brake the speed of rotation of the engine, and means operated by said brake operating means for locking said fuel supplying device against operation.
5. The combination of an internal combustion engine having an electric ignition plug, an auxiliary electric starting motor, means for supplying an electric current to said plug and motor, a device for supplying fuel to said engine, means for maintaining said device inoperative, movable means operative in successive steps to close the circuit through said ignition plug, then through said starting motor and then to release said fuel supplying device thereby to start the engine, means for braking the speed of rotation of the engine, and means between said movable means and braking means for preventing actuation of one of said means until the complete operation of the other has been performed.
6. The combination of an internal combustion engine having an electric ignition plug, an auxiliary electric starting motor, means for supplying an electric current to said plug and motor, a device for supplying fuel to said engine, means for maintaining said device inoperative, a lever operative in successive steps to close the circuit through said ignition plug, then through said starting motor and then to release said fuel supplying device thereby to start the engine, and means for automatically returning said lever to its initial position.
7. The combination of an internal combustion engine having an electric ignition plug, an auxiliary electric starting motor, means for supplying an electric current to said plug and motor, a device for supplying fuel to said engine, means for maintaining said device inoperative, movable means operative in successive steps to close the circuit through said ignition plug, then through said starting motor and then to release said fuel supplying device thereby to start the engine, and means for breaking the circuit through said plug independently of the movement of said movable means.

In testimony whereof I have signed my name to this specification.

CARL AUGUST RUDQVIST.
